UNITED STATES PATENT OFFICE.

CHARLES L. KELLER, OF CINCINNATI, OHIO, ASSIGNOR TO THE RICHARDSON COMPANY, OF LOCKLAND, OHIO, A CORPORATION OF OHIO.

ROOFING DEVICE.

Application filed June 25, 1923. Serial No. 647,504.

To all whom it may concern:

Be it known that I, CHARLES L. KELLER, a citizen of the United States, and a resident of Cincinnati, in the county of Hamilton and State of Ohio, have invented certain new and useful Improvements in Roofing Devices, of which the following is a full, clear, and exact description, reference being had to the accompanying drawing, 10 forming part of this specification.

My invention relates to devices for use in laying roofs, particularly where using composition shingles and strips, and also to roofs as laid by the use of such devices.

15 In a co-pending application, Serial No. 631,700 filed April 12, 1923, covering an invention of this application, I have set forth and described a device for use in laying roofs and individual shingles, which device is in the form of an S-hook and is so placed in the roof as to serve as a means for fixing the back lap in shingle roofs.

20 The present invention covers the more general aspects of said structure, in which a double hook or S-hook is not necessarily used, and the back lap is still provided for, as well as spacing and hold-down features.

25 The term back lap refers to that portion of a course of shingles or a single shingle, when laid on a roof, which lies beneath the next course, but one, of shingles on the roof. Thus there is a first course of shingles, laid side by side in interspaced relation, then a second course of shingles laid over this course, and interspaced to leave exposed a narrow portion of the first course, and finally a third course, which lies over the second and blocks off the exposure of the first course. The back lap is the extent 30 that the third course lies over the first course.

35 In roofing, the danger point of the roof is the flue-like space left where the third course lies over the slot between shingles of the second course, as here both fire, wind, and water can be driven up to contact with the sheathing that covers the roof beneath the shingles. The underwriters' requirements as to back lap are specific, and the 40 cutting down of the back lap dimension at once gives greater coverage of shingles on roofs.

45 My new devices have the function of holding down the shingles of each course with an overlying hook, spacing the shingles of next underlying course, and prescribing the distance from the top or back of a second underlying course, and the held-down butt or front edge of the course engaged by the overlying hook. They also 50 have the function of serving as a dam to prevent fire, wind and water getting up to the roof sheathing, thereby cutting down and also insuring the minimum required back lap.

55 The essential difference in the showing of the invention in this application over my former application, is that a hook for engaging around and under the back ends or covered ends of shingles in a roof, is 60 there provided for, which makes for a more expensive hook, and also limits somewhat the different ways of obtaining irregular exposures by means of shingles in a roof, likewise hinders somewhat the speed of 65 application.

70 Thus my former application is a species of hook, and this application shows and describes the hooks shown in the co-pending case and also several other forms of hook, 75 and covers the general aspects of all hooks and in particular the special hooks that differ from those in the co-pending case.

I accomplish the objects set forth above by that certain construction and arrangement 80 of parts to be hereinafter more specifically pointed out and claimed.

In the drawings,

85 Figure 1 is a perspective view of one of the hooks.

Figure 2 is a like view of another form of the hooks.

Figure 3 is a sectional view of a roof showing the use of the hooks.

Figure 4 is a fragmentary plan view of 90 a roof showing one form or effect to be gained with my novel device.

Figure 5 is a like plan view of a roof showing another form or effect gained.

Figure 6 is a further plan view showing 95 another form or effect to be gained.

Figure 7 is a perspective of the hook shown in my co-pending application.

I have shown in Figure 1 a back lap

hook, having the body portion 11, which is the length of a desired back lap and the hook portion 12, which in one sense is a hook, and in another is a downwardly bent abutment, which is intended to be laid against the back end of the shingle on which the hook is mounted. At the front end of the body portion is a hook having a stand 13^a, and a top 13, this hook being 5 of the width necessary to bridge the space between two shingles laid alongside of it, and of the height to pass up along the butt end of a shingle laid on top of the two shingles just referred to, with the top 13 10 of the hook lying over the top surface of the said butt.

In Figure 2 the hook has the body portion 11, stand 13^a and top 13, for a single hook, and at the other end of the body portion there is no hook at all. In use, the back 20 end of the body portion is used as a guide in obtaining a definite back lap, the roofer endeavoring to bring the back of the body portion in line with the back edge of the shingle on which the hook is mounted.

In each form of hook I have shown a nail hole at 14, through which a nail is driven to hold down the hooks.

In Figure 7 I have shown a hook device 30 having body portion 11, hooks 13, 13^a, and another hook at the back end having the depending portion 12, with the additional bend 12^a, forming a member to engage beneath the back end of a shingle on which 35 the device is mounted.

It may be observed that the hook device of Figure 1 can be used as is the device of Figure 2, by pressing the portion 12 down into a shingle on which the hook device of 40 said Figure 1 is mounted.

Referring now to the roof on which this form of hook is to be used, it should be noted that it can be used with any style of shingle, either individual or strip, and in 45 a wide variety of shapes. I have shown the use in connection with the plain rectangular shingle, which is the standard in roof laying at the present time, and of which the vast majority of roofs are laid.

Referring first to Figure 3 it will be noted 50 that the shingles are laid over roof sheathing 5, there being shingles shown in courses 1, 2 and 3. I have not shown a starting strip in this view, and it will be understood 55 that the showing has been selected to illustrate three courses of shingles without regard to the remainder of the roof. When shingles at 1 are laid down on the roof, a hook is nailed down at, say, the center 60 of the back of each shingle in the course. The hook of Figure 1 is shown as in use, with the abutment at 12 set against the back edge of the shingles 1.

In the laying of the course 2, the shingles 65 thereof are arranged so that the hooks lie

between each pair of the shingles 2, serving as the spacing guide, and resulting in the stands 13^a, lying across the gap between the shingles 2, and serving as a dam against wind, fire, or water working up through 70 the gap. Hooks are then mounted at, say, the center of the backs of the shingles 2, in the same manner as described on shingles 1.

When course 3 is laid, the shingles 3 are 75 spaced apart by the hooks nailed down onto shingles 2, and the hooks 13, 13^a of the devices on course 1 are engaged over the butts or front ends of said shingles 3.

The result of this laying method is shown 80 in Figure 4, wherein it will be noted that the distance from the butts of the shingles of course 3 to the back of shingles of course 1, is defined by the body portion of the hook devices. This distance, as has been noted, is 85 that termed "back lap".

It will be noted that the spacing of shingles in course 2 is defined by the hooks on course 1, and that the gap left between shingles 2, running up beneath the shingles 90 of course 3, is completely blocked off.

In Figure 5 I have shown a roof which is laid with the exposure of the first course of shingles on the starting strip being more than half of the length of the shingles of 95 this course when the length of the back lap hooks has been subtracted. Thus if the shingles of the first course are 14 inches long, and the back lap hooks 2 inches long, an even exposure on the roof will be obtained when proceeding as indicated in Figure 4, if the first course is exposed exactly 6 inches. By changing the width of the starting strip, however, and placing the first row of hooks on the back of the starting strip, 100 different effects can be gained.

Thus I have shown what may be assumed to be a ten inch starting strip 5, two inch hooks, and fourteen inch shingles, using the hooks of Figure 1 or Figure 7. The result 110 is that the shingles of course 1 will be laid so that their lower edges register with the lower edge of the starting strip. The hooks on the starting strip serve as side spacers for course 1. The shingles of course 2 are 115 then laid, and hooked under the hooks 13, of the hook devices, being spaced laterally by the hooks on course 1.

It may be observed that this brings about 120 an exposure of eight inches of the shingles of course 1, and that when course 3 is laid in like manner, as heretofore described, that the shingles of this course will overlap the shingles of the second course ten inches, leaving a four inch exposure of course 2. 125 This results because course 1 is fourteen inches long, and the hooks two inches long, and eight inches of course 1 has been exposed, so that the lower ends of the hooks on course 1 will lie two inches from the 130

back course 1, while the butts of course 1 leave a four inch space, throughout which course 2 is not covered.

The same result will apply to course 4, 5 in the showing Figure 5, which will leave exposed the full eight inches of course 3.

Thus by starting off courses 1 and 2 in an irregular manner, the remaining alternate courses will be alike exposed to courses 1 10 and 2.

In Figure 6, I have shown an effect which can be gained, either with the use of shingles of equal width but different length, or by the use of the hook devices of Figure 2 15 particularly or Figure 1.

In this showing, the hooks have been laid on the starting strip in an irregular manner, so that the back ends of the hooks do not register with the back edge of the 20 starting strip, in some instances. This is shown at A, B, and C on the starting strip. Course 1 will then be laid over the starting strip, with a regular lower edge.

Course 2, however, will have a wavy out-line, as laid, similar to the thatch effect. The hooks on course 2 may also be arranged with the back ends not always in register with the back of the shingles, as illustrated at D, for example, resulting in throwing 30 the shingles of course 3 out of line, as to their butts.

That result is, that the roof may have any kind of varied effect that is desired, but that, so long as no hook is laid with 35 its back end located beyond or overlying the back end of the shingle on which it is mounted, the roof will always have a back lap throughout, which corresponds or is greater than that for which the hooks were 40 built.

Where shingles of different length are used, and the back lap hooks used in each course, there will never be any danger of leaving an exposure through the roof, and 45 all gaps between shingles will be sealed off by the standing portions 13^a of the hook devices.

Also if the shingles are to be laid with a staggered relation in courses of two thirds 50 and one third, it is merely required that the two first sets of hooks be properly set, and the rest of the roof will follow suit.

In time of laying a roof, using my hooks, the saving is tremendous, as no lines have 55 to be drawn on the roof, and a boy can do the work, requiring ordinarily a highly skilled workman. Also a defective shingle can be slipped out of the roof and replaced, at any time, by merely pulling 60 up the hook nailed down on the defective shingle, and releasing the butts of adjoining shingles from their hooked down engagement.

It makes no difference what length of 65 shingle is used or whether the same length

is used throughout the roof, so far as getting a tight roof is concerned. Also where shingles of like width and length are laid in a roof, and the first two courses properly arranged, the remainder of the roof 70 builds itself, as it were, provided the hooks are used as intended.

The use of clinching devices instead of hooks, so long as the back lap protection feature is provided, will come within my 75 invention, as will changes in shape, omission of nail holes in the S-hook style of Figure 7, and of my former application.

Having thus described my invention, what I claim as new and desire to secure 80 by Letters Patent, is:—

1. A roof formed of composition shingles, laid in courses, the individual shingle units being spaced apart in courses sufficient to cast a shadow, and the courses overlapped, 85 and securing devices formed of metal strips having body portions each provided with a nail hole intermediate its ends, and with a hook at the lower end, said hook having a stand of a height equal to the thickness 90 of two shingles, and a return bent end, said securing devices laid with their body portions placed against the shingles, nails extending through the body portions, and shingles and into the roof deck, and the upper ends of the body portions aligned with the top ends of the shingles, the shingles interspaced throughout the roof by the said securing devices, and the hooks engaging the butts or lower projecting ends 95 of the shingles, said stands of the hooks extending from the shingles on which the hooks are placed, and damming up the spaces between the shingles interspaced by the securing devices, whereby the back lap 100 of the roof may be cut down and exactly determined by the length of the body portions, and curling of shingles prevented at the point where they overlie the dammed-up spaces. 105

2. A roofing formed of composition shingles, laid in courses, the individual shingle units being spaced apart in courses sufficient to cast a shadow, and the courses overlapped, and securing devices formed of metal strips having body portions each provided with a nail hole intermediate its ends, and with a hook at the lower end, said hook having a stand of a height equal to the thickness of two shingles, and a return bent end, said securing devices laid with their body portions placed against the shingles, nails extending through the body portions, and shingles and into the roof deck and the upper ends of the body portions aligned with the top ends of the shingles, the shingles interspaced throughout the roof by the said securing devices, and the hooks engaging the butts or lower projecting ends of the shingles, said stands 115 120 125 130

of the hooks extending from the shingles on which the hooks are placed, and damming up the spaces between the shingles interspaced by the securing devices, where-
5 by the back lap of the roof may be cut down and exactly determined by the length of the body portions, and curling of shingles prevented at the point where they overlie

the dammed-up spaces, said body portions of the securing devices having depending ¹⁰ bends at the ends away from the hooks, thereby providing an abutment for engagement against the back ends of shingles against which the body portions are nailed.

CHARLES L. KELLER.
